ROLLER SHADE FIXTURE

Robert C. Skinner, Santa Monica, Calif.

Application September 15, 1934, Serial No. 744,179

11 Claims. (Cl. 248—267)

This invention relates to an improved roller shade fixture and has for one of its principal objects the preventing of fraying of the edges of the ordinary window shade, which fraying is usually caused by accidental contact of the edges with the supporting fixture, and which contact is positively eliminated by the use of this invention.

Another important object of the invention is to provide, in combination with a fixture for roller shades or the like which will prevent fraying, a means for stopping undesirable upward motion of the window shade bar past the desired upper limit of the travel of the shade itself which sometimes happens with the ordinary fixture and with the result that the shade cannot be operated until this condition is remedied.

Another and further important object of the invention is to provide an inexpensive bracket for supporting roller shades of this type and protecting the edges of the same against fraying, and also to prevent undesirable whirling when the shade has reached its uppermost limit of travel, which fixture shall be economical to manufacture, simple to install and not likely to get out of order.

A further and another important object of the invention is to provide a type of roller shade fixture for preventing edge fraying and undesirable whirling at the top of the travel of the shade which shall be conveniently and readily adaptable with slight modifications for supporting any type of shade and also for use with all types of windows and window frames.

Other and further important objects of the invention will be apparent from the disclosures in the accompanying drawings and following specification.

The invention, in a preferred form, is illustrated in the drawings and hereinafter more fully described.

In the drawings:

Figure 1 is a front elevation of the improved roller shade fixture of this invention, showing the same as applied to a window frame having French windows therein and with the shade in position, parts of the apparatus being shown in dotted lines.

Figure 2 is an enlarged view of the fixture shown in Figure 1, portions of the window frame being broken away.

Figure 3 is a view similar to Figure 2 illustrating a slight modification of the invention and showing the same as applied to a window frame having windows slidably mounted therein.

Figure 4 shows still another modification of the invention.

Figure 5 is a perspective view of the left-hand bracket with its attachment shown in Figures 1 and 2, the two structures being shown as 5 separated for purposes of better illustration.

Figure 6 is a perspective view of a slightly modified form of the supporting bracket shown in Figure 5, the same being adapted to have the slideable element of Figure 5 mounted thereon. This illustration also corresponds with the showing of Figure 3.

Figure 7 is a perspective view of a bracket and slide such as shown in Figure 4, the bracket and slide being separated for better illustrative 15 purposes.

As shown in the drawings:

The reference numeral 10 indicates generally a window frame to which the improved roller shade brackets of this invention can be applied, 20 this particular frame comprising one having French windows or the like 12 mounted therein by hinges 14.

The shade is shown at 16 and is of the ordinary variety having the usual pull 18.

As best shown in Figure 2, the supporting brackets for the shade are composed of metal having base elements 20 and 22 adapted to be fastened by screws or the like 24 to the frame 10. These screws are preferably mounted in 30 open and enlarged slots 26 so that the bracket can be readily removed, if desired. Each of the brackets has the usual extensions 28 and 30 respectively, which extensions are slotted or pierced to receive the corresponding ends of a 35 roller shade.

Each of the brackets has an integral inwardly extending tongue 32—34 respectively, each of the tongues being slotted as shown at 36, thereby dividing the tongue into two portions, the narrower portion having a helical spring 38 mounted thereon.

Slidably fitted upon each of the tongues 34 is the edge protecting element of this invention which comprises essentially a base member 40 45 shaped as best shown in Figure 5 having slot 42 formed in offset portions thereof for the reception of the tongue 32. Integral with each base and extending at right-angles thereto is a guard element 44 having a circular opening 46 formed 50 therein through which opening the wooden roller or support of the shade proper is adapted to pass so that the shade itself can be suitably mounted on the brackets 28—30. The cloth portion of the shade is adapted to be contacted by 55

the guard 44 when the shade is pulled up and down, this contact being assured by the action of the spring 38 which is quite light, and the guard itself is slightly convexed on the face 5 which contacts the shade so that a rounded surface is always presented to the shade edge. This assists in guiding the shade vertically in its movement and positively prevents the edges of the same from contacting portions of the brackets 10 20, 22, 26 or 28, which, heretofore, has always been undesirable as tearing and fraying of the edges of the shade proper almost invariably resulted from such contacts.

The downwardly extending apron of the guard 15 is also rearwardly rounded so as to materially assist in this protective action.

The slideable element 40 has integral therewith an arm 48 (Figure 5) upon which is mounted a resilient bumper element or the like 50 preferably composed of rubber which arm and bumper extend sufficiently forwardly from the bracket 32 so as to contact the lower end of the shade with its usual reinforcing slat, this being thicker than the rest of the shade and, therefore, 25 will obviously contact the bumper 50 when the shade reaches the extreme upper limit of its travel and has been wound on the roller. A similar bumper is mounted on the bracket 34 so that both ends of the bottom of the shade will be 30 stopped, thereby preventing undesirable whirling of the shade and roller at the top of the window frame if too suddenly released.

A modified form of construction is shown in Figure 3 wherein a bracket 52 is provided 35 adapted to be mounted on the inner face of a window frame 54 and having an extension 56 for the reception of a combination guide and bumper 58-60 which can be identical with the guide and bumper 44-50 of Figure 2. Another 40 difference between this bracket and that shown in Figures 1 and 2 is the latching element 62 at the end of the bar 56, whereby the slideable member 58-60 is locked in position. This is better illustrated in Figure 6 which also shows a positioning of the helical spring 64 at the bottom of the bracket rather than at the top as in the structure illustrated in Figures 1, 2, and 5.

The complementary element 66 which holds the other end of the shade is similar in structure and also has a locking or latching projection 68 as best shown in Figure 4.

A further modification is shown in Figures 4 and 7 wherein a bracket 70 is shown devised for attachment to the outer face of a window frame 55 or the like and with an outwardly projecting integral arm 72 having a slot 74 therein, the slot being positioned centrally of the arm and with the usual spring 76 mounted in the slot. A slideable element 78 is mounted on the bar 72, this 60 including merely a guard 80 of a form slightly different than the form shown in Figure 5, and the bumper 50-60 is eliminated, as it is possible that the same may not be desirable in some constructions. The complementary element 82 65 is similarly constructed as best shown in Figure 4.

It will be evident that herein is provided a combination bracket, guard and bumper for window shades of the roller type which will constitute quite an improvement over the ordinary brackets or supports now in use as the objectionable fraying of the edges of the shade will be definitely eliminated and another annoyance due to undesirable whirling of the shade and

roller around its axis at the top of the travel of the shade will be avoided. Furthermore, the entire combination, brackets, guards, and bumpers, are economical of construction, readily installed, simple of operation and not likely to 5 get out of order.

I am aware that many changes may be made and numerous details of construction varied throughout a wide range without departing from the principles of this invention, and I, therefore, 10 do not propose limiting the patent granted hereon otherwise than as necessitated by the prior art.

I claim as my invention:

1. A roller shade fixture, including a supporting bracket and a combination guard and bumper on the bracket.

2. A roller shade fixture, including a supporting bracket and a combination guard and bumper slidably mounted on the bracket.

3. A roller shade fixture, including a supporting bracket, and a combination guide, guard and bumper on the bracket.

4. A roller shade fixture, including a bracket and a shade edge guard slidably mounted on 25 said bracket, said guard comprising a plate having an opening through which the roller passes and a flange adapted to contact and guide the edge of the shade in its movement, and an extension on the bracket adapted for the slideable 30 reception of the guard.

5. A roller shade fixture, including a bracket and a shade edge guard slidably mounted on said bracket, said guard comprising a plate having an opening through which the roller passes 35 and a flange adapted to contact and guide the edge of the shade in its movement, and an extension on the bracket adapted for the slideable reception of the guard, together with a spring on said extension for resiliently forcing the guard 40 against the shade edge.

6. A roller shade fixture, including a bracket and a shade edge guard slidably mounted on said bracket, said guard comprising a plate having an opening through which the roller passes 45 and a flange adapted to contact and guide the edge of the shade in its movement, and an extension on the bracket adapted for the slideable reception of the guard, together with a spring on said extension for resiliently forcing the guard 50 against the shade edge, and an arm integral with the guard plate, said arm comprising a bumper and stop for the lower edge of the shade.

7. A roller shade fixture, including a bracket and a shade edge guard slidably mounted on 55 said bracket, said guard comprising a plate having an opening through which the roller passes and a flange adapted to contact and guide the edge of the shade in its movement, and an extension on the bracket adapted for the slideable 60 reception of the guard, together with a spring on said extension for resiliently forcing the guard against the shade edge, and an arm integral with the guard plate, said arm comprising a bumper and stop for the lower edge of the shade, and a resilient covering over said arm.

8. A roller shade fixture, including a supporting bracket, an arm integral therewith extending in a direction parallel to the shade roller, said arm having a slot extending longitudinally thereof, and a combination guard and bumper slidably mounted on the arm.

9. A roller shade fixture, including a supporting bracket, an arm integral therewith extend-

ing in a direction parallel to the shade roller, said arm having a slot extending longitudinally thereof, and a combination guard and bumper slidably mounted on the arm, and latch means comprising a projection at the end of the arm for retaining the guard and bumper thereon.

10. A roller shade fixture, including a supporting bracket, an arm integral therewith extending in a direction parallel to the shade roller, said arm having a slot extending longitudinally thereof, and a combination guard and bumper slidably mounted on the arm, and latch means comprising a projection at the end of the arm

for retaining the guard and bumper thereon, and limiting the extent of travel of same.

11. A roller shade fixture, including a supporting bracket, an arm integral therewith extending in a direction parallel to the shade roller, 5 said arm having a slot extending longitudinally thereof, and a combination guard and bumper slidably mounted on the arm, and a helical spring mounted on the arm in the slot adapted to contact the combination guard and bumper 10 for forcing the guard member resiliently against the shade edge.

ROBERT C. SKINNER.
